UNITED STATES PATENT OFFICE.

HENRY DOHERTY AND JOSEPH WADSWORTH, OF PATERSON, NEW JERSEY.

DESIGN FOR A HANDKERCHIEF.

SPECIFICATION forming part of Design No. 12,936, dated May 23, 1862.

Application filed April 11, 1862. Term of patent 3½ years.

To all whom it may concern:

Be it known that we, HENRY DOHERTY and JOSEPH WADSWORTH, citizens of the United States, residing at Paterson, Passaic county, State of New Jersey, have invented and produced a new and original Design for Handkerchiefs, of which the following is a specification, reference being had to the accompanying drawing, forming a part thereof, in which—

10 A represents the body or general surface of the handkerchief.

B represents a figure which I will proceed to describe.

15 a represents stems that were cut from the stalk on which they grew.

b represents unfolded leaves on the stems a.

Above the open leaves b there appear leaves not yet unfolded, and from under the leaves there appear sprigs e.

c represents opening petals of a flower, and 20 d represents the part of the flower that is more fully open; and a', b, c, d, e, and f represent a lily with its crown f in full view, and its stems, leaves, &c.

Having described our new and original design, what we claim, and desire to secure by Letters Patent, is—

The design for handkerchiefs, having a body, A, and a lily, B, formed in each corner of the same, as shown and set forth.

HENRY DOHERTY.
JOSEPH WADSWORTH.
